[57] CLAIM

The ornamental design for an article carrier tie-down bracket, as shown and described.

DESCRIPTION

FIG. 1 is a perspective view of an article carrier tie-down bracket according to the present invention shown in conjunction with a portion of a cross rail of an article carrier which is shown in broken lines for illustrative purposes only;

FIG. 2 is a side elevational view thereof, the opposite side being a mirror image of that shown;

FIG. 3 is a rear elevational view thereof;

FIG. 4 is a front elevational view thereof;

FIG. 5 is a top plan view thereof; and

FIG. 6 is a bottom plan view thereof.
